Inventor

Louis T. Roberts

UNITED STATES PATENT OFFICE.

LOUIS T. ROBERTS, OF TURTLE CREEK, PENNSYLVANIA.

FLEXIBLE-SHEET-SECURING MEANS.

1,288,201.

Specification of Letters Patent. Patented Dec. 17, 1918.

Application filed May 14, 1918. Serial No. 234,457.

To all whom it may concern:

Be it known that I, LOUIS T. ROBERTS, a subject of the King of Great Britain, and a resident of Turtle Creek, in the county of Allegheny and State of Pennsylvania, have invented certain new and useful Improvements in Flexible-Sheet-Securing Means, of which the following is a specification.

This invention relates to improvements in means for securing the ends of flexible sheets or strips of material such as paper, in engagement with the roller upon which they are wound.

The principal object is to provide an attaching means for the end of the paper strips whereby the same is prevented from becoming torn, frayed or broken, in a manner to materially damage the same.

A further object is to provide a fastening means which may be readily applied to the extending ends of sheets, with special reference to rolled music sheets used in connection with self-playing instruments of the piano type, the device preventing the mutilation of the end of the sheet and consequent damage to the same, it being well recognized that such securing means that are at present employed are easily torn away, damaging or totally destroying the value of the music sheet.

These and other like objects are attained by the novel construction and combination of parts hereinafter described and shown in the accompanying drawing, forming a material part of this disclosure, and in which:—

Figure 1 is a perspective view, showing the end of a conventional type of music sheet, and indicating the application of the invention thereto.

Fig. 2 is a perspective view, showing one of the forms of sheet music rollers as ordinarily employed in self-playing pianos and like types of instruments, and

Fig. 3 is an enlarged longitudinal sectional view taken on line 3—3 of Fig. 1.

In the drawings the numeral 10 indicates a conventional type of music sheet, the same containing perforations 11, and formed with beveled end edges 12 as is usual.

The roller upon which the sheet is wound, as indicated in Fig. 2 of the drawing, consists of a cylindrical body 15, having guide flanges 16 at its ends, the roller being pivotally mounted on projecting pins 17, arranged at the ends axially thereof. Centrally of the roller is a transverse recess 18,

in which is secured a hook element 19, the roller throughout being of the usual type of commercial construction.

The invention consists of the use of a thin, narrow strip of metal 20, bent upon itself, forming a loop 21, the rearwardly turned lower element 22 of the strip, together with the upper element 20, being formed with a plurality of corrugations 24 adapted to be disposed upon opposite sides of the paper 10, so as to firmly grip and engage with the same, while in the loop 21 is secured an open eye or ring 25, engageable with the hook 19 secured in the roller.

In order to further secure the clip elements upon the opposite sides of the paper sheet 10, reinforcing sheets of fabric 28 are cemented or otherwise affixed to the extending end of the paper sheet so as to embrace the metallic clip elements, holding them securely to the paper in a manner which will be readily understood, the showing in Fig. 1 indicating one of the reinforcing coverings 28 partially rolled or coiled upon itself so as to disclose the construction.

Thus the ends of paper sheets are firmly grasped between the corrugated surfaces of the metallic clip, the undulations or sinuosity of which are transferred to the end of the paper strip, permitting a very considerable pull to be exerted on the ring 25 without doing any damage to the music sheet, while the reinforcing elements 28 add materially to the strength of the joint attained, without interfering with the flexibility of the sheet or being objectionable in any manner whatever.

While the foregoing shows a preferred embodiment of the invention, it will be readily understood that the same is applicable for many other purposes than that of connecting music sheet ends with their rollers and further, that the drawing, together with the description, is to be regarded as descriptive rather than limitative, as obviously many other forms embodying the same general principles can be employed for the same or like purpose.

Having thus described my invention what I claim as new, and desire to secure by Letters Patent is:—

In a flexible securing device, the combination with the sheet to be secured, of a thin strip of flexible metal folded closely upon itself, presenting two parallel extending elements adapted to engage opposite sides of

said sheet, a plurality of corrugations formed in register in both of said extending elements adapted to grip said sheet, said elements having flat terminals, a ring loosely engaged in the folded loop portion of said strip beyond the end edge of said sheet, and reinforcements secured upon the end of said

sheet upon both sides thereof, said reinforcements being firmly adherent to the sheet and covering said extending elements whereby 10 they are held in fixed position.

In testimony whereof I have signed my name to this specification.

LOUIS T. ROBERTS.
